VAPOR ELECTRIC DEVICE

William E. Pakala, Forest Hills, Pa., assignor to
Westinghouse Electric Corporation, East Pittsburgh, Pa., a corporation of Pennsylvania

Application March 20, 1947, Serial No. 735,991

19 Claims. (Cl. 315—201)

1

My invention relates to a vapor electric device, and particularly to a control circuit using a single controlled electric valve for applying periodic excitation to two alternately conducting vapor electric valves.

This is a continuation-in-part of my application Serial No. 531,096, filed April 14, 1944, now abandoned, and assigned to the same assignee as this application.

In the construction of vapor electric devices of the make-alive type, the equipment for producing the excitation impulses is of substantially uniform size regardless of the power rating of the rectifier. It thus frequently happens that for small power ratings the control equipment occupies more space than the rectifier per se. Also, it has heretofore been necessary to utilize a control valve for each valve of the main rectifier, thus increasing the cost and size of the excitation equipment.

According to my invention, I materially reduce the size and space requirements of the excitation system by utilizing a single controlled electric valve to apply excitation impulses to two alternately conducting vapor electric valves.

In the construction according to my invention, a capacitor is arranged in charging relation to a suitable source of control energy and alternately discharged through the make-alive electrodes of a pair of valves by means of a control valve in a common return circuit from the load device to the impulsive capacitor.

It is accordingly an object of my invention to provide a control circuit utilizing a single control valve to apply excitation impulses to a plurality of vapor electric devices.

It is a further object of my invention to provide a control system having a minimum number of parts.

It is a further object of my invention to provide a control system capable of being installed in the minimum of space.

It is a further object of my invention to utilize a single control valve to control consecutive impulses of opposite polarity.

It is a further object of my invention to provide means responsive to the available control energy to trigger the control valve.

Other objects and advantages of my invention will be apparent from the following detailed de-

2

scription, taken in conjunction with the accompanying drawings, in which:

Fig. 1 is a schematic illustration of a vapor electric converter according to my invention;

5 Fig. 2 is a modification similar to Fig. 1 showing the utilization of a mercury-pool type control tube;

Fig. 3 is a diagrammatic illustration of the voltage and current characteristics of the control system according to my invention;

10 Fig. 4 is a further modification showing the utilization of a winding to complete the return circuit of the capacitor;

Fig. 5 is a further modification showing the 15 utilization of high voltage in the main portion of the excitation circuit;

Fig. 6 is a modification similar to Fig. 1 showing a direct connection of the excitation circuit to the anode terminals of the converter;

20 Fig. 7 is a schematic illustration showing the adaptation of my system to a conversion circuit utilizing a plurality of pairs of alternately conducting valves;

Fig. 8 is a schematic illustration of a typical 25 embodiment of a conversion system utilizing my invention; and

Fig. 9 is a diagrammatic illustration of the 30 voltages applied to the grid of a control tube as utilized in Fig. 8.

In the illustrated embodiment of my invention according to Figs. 1 and 8, an alternating-current supply circuit 10 is connected to a load circuit 11 by means of a converter transformer 12 and the flow of current between the circuits 10

35 and 11 is controlled by means of a pair of alternately conducting valves 13 and 14 of the make-alive type, each of said valves 13 and 14 comprising an anode 15 connected to a corresponding terminal of the rectifier transformer 12, a va-

porizable reconstructing cathode 16 of suitable material, such as mercury, placed in spaced insulating relation to the anode 15, and an excitation electrode 17, preferably of the make-alive type, comprising a pointed, rod-like member of high resistance material in substantially permanent contact with the pool of cathode material.

It is usually desirable to provide suitable switching mechanism 52 between the alternating-current circuit 10 and the rectifier transformer 12, and also to provide switching mecha-

nism 72 between the converter and the load circuit 11.

The excitation system comprises a suitable source of alternating current having a frequency corresponding to the frequency applied to the converter valves 13-14. I have herein shown the control potential as being supplied through switch 31 from the alternating-current circuit 10, preferably through a suitable phase-shifting device 20 to the primary winding of a transformer 21 which is connected in charging relation to an excitation capacitor 22. The phase shifter 20 may be entirely omitted when only a moderate phase shift is desired, thus further reducing the size and weight of the control cabinet. Preferably an impedance 23, usually in the form of a reactor, is provided between the charging transformer 21 and the capacitor 22, not only to control the rate of charge of the capacitor 22 but to control the follow current from the charging transformer 21 upon discharge of the capacitor 22. It will thus be seen that the capacitor 22 will be alternately charged during the consecutive half-cycles of the potentials of the control source.

The cathodes 16 of valves 13-14 are connected together by the common cathode connection 26. A common return circuit for the make-alive electrodes 17 includes a conductor 32 extending from the common cathode connection 26 to a mid-tap 33 in a polarity responsive device herein shown as a pair of oppositely poled unidirectional conductors 29-30 connected across the capacitor 22 and each being conductive from the mid-point 33 toward its respective capacitor terminal so that current can flow from the conductor 32 to either terminal of the capacitor 22 depending upon the polarity of the capacitor charge.

The connection 24 contains a unidirectional conductor 27 while connection 25 contains a unidirectional conductor 28. The unidirectional conductors 27 and 28 are so poled that when one terminal of the capacitor 22 is positive, current will flow through unidirectional conductor 27, connection 24, make-alive electrode 17 and cathode 16 of valve 13 to the cathode terminal 26 thence through connection 32 and unidirectional conductor 30 to the negative terminal of the capacitor 22; then on the alternate polarity, the current flows through unidirectional conductor 28, connection 25, the make-alive 17 and cathode 16 of valve 14 to the cathode terminal 26 thence through connection 32 and unidirectional conductor 29 to the negative terminal of capacitor 22. It will be seen that the unidirectional conductors 27-28-29-30 thus provide a bridge-type rectifier across the terminals of the capacitor 22 with the unidirectional current-carrying connection 32 across the unidirectional terminals 26 and 33.

The make-alive electrodes 17 of alternately conducting valves 15 are connected in series circuit relation to unidirectional conductors 27 and 28 respectively in alternate arms of the bridge circuit. The make-alive electrodes thus alternately provide the load on the system. Obviously, instead of directly coupling the make-alive electrodes, they may be indirectly coupled as by means of the transformer 48.

In order to control the flow of current in the load device 17, a controllable electric valve 35 is connected in the unidirectional current-carrying connection 32. Preferably, the valve 35 is of the gaseous grid controlled variety and may have a hot cathode as shown in Fig. 1, or a pool-type

cathode as shown in Fig. 2. The grid 36 of valve 35 is supplied with direct-current biasing potential from any source 37 of direct current. The direct current is preferably variable and, in any event, is provided with means to vary the applied potential as by a voltage divider 38.

In the operation of this embodiment of my invention, I will assume that the polarity is such that the upper side of the capacitor 22 is at a positive potential and that positive potential is applied to the anode of the electric valve 13 of the converter. The device will then be put in operation by controlling the grid 36 of the controlled valve 35 in the return circuit 32 to permit discharge of the capacitor 22 through the make-alive electrode 17, the common connection 26, the controlled electric valve 35 and, if necessary, through current-limiting resistor and unidirectional conductor 30 to the negative side of the capacitor 22.

As will be seen from the diagrammatic illustration of Fig. 3, the voltage e_c of the capacitor 22 is adjusted so as to have sufficient potential derived from the supply potential e_0 at the desired firing instant to produce a current impulse 40 having sufficient magnitude to create a cathode spot in the converter. Since there will be a substantial component of potential applied through the charging impedance 23 and the unidirectional conductor 27 to the make-alive electrode 17, current 41 will continue to flow until such time as the voltage e_c drops to a potential which will fail to produce current flow through the impedance of the circuit. The excitation impulse 40 therefore has a steep wave front of high amplitude for a short duration and a follow current 41 of trailing wave shape for the continuation of the excitation cycle.

The modification according to Fig. 2 is identical with that of Fig. 1, except that a mercury-pool control valve 35' has been substituted for the hot-cathode control valve 35 of Fig. 1. A starting electrode 39 preferably of the make-alive type is provided and the system is put into operation by closing a starting switch which permits the excitation impulse 40 to initiate a cathode spot in the control valve 35' which is then maintained by means of a keep-alive arc from any suitable source 34, while the grid 36 is controlled to control the actual beginning of current impulses through the alternately conducting valves 13-14 of the converter.

In the modification according to Figs. 4 and 7, the return circuit 32 is completed by means of a winding 45 of relatively high impedance such as a transformer winding connected across the terminals of the excitation capacitor 22, and the return circuit 32 is connected to an intermediate tap 46 in the high impedance winding 45.

Fig. 5 discloses a further modification particularly adapted to the utilization of high potential control devices. The supply transformer 21' may be either a double-winding or a single-winding transformer, the capacitor 22 being charged to high potentials by connection to the secondary or high potential terminals of the transformer 21'. The discharge circuit is then completed by means of a firing transformer 48, the primary 49 of which is alternately energized from the excitation capacitor 22 and the current is then stepped up or rather the voltage is reduced to the necessary potential for operating the make-alive electrodes 17 by means of secondary windings 50-51 energized by the current impulse 52 in the firing transformer 48. In order to prevent

reverse current through the make-alive electrodes 17, a unidirectional conductor 53 or 54 is placed in series with each of the make-alive electrodes 17. Therefore, the secondary windings 50—51 will alternately carry current, depending upon the polarity impressed on the firing transformer 48.

The modification of Fig. 6 is substantially similar to the modification of Fig. 1 except that the charging transformer 21 and its associated phase shifter 20 has been omitted, and the impulsive capacitor 22 directly connected across the terminals of the rectifier transformer 12. For purposes of balance, I prefer to split the charging impedance 23 and to place a section 23' of this impedance on each side of the capacitor 22. The operation is otherwise identical with the operation as described according to Fig. 1.

Fig. 7 illustrates the method of employing my control system of Fig. 4 for controlling a plurality of pairs of converter valves as is usually done in commercial circuits. The polyphase circuit 10' is connected to the direct-current circuit 11 by means of a multiplied phase transformer 12' herein illustrated as of the double three-phase variety and the resultant pairs of valves are each controlled by their individual impulsive circuit. The grid potentials of the control tubes 35 may readily be controlled by a variable resistor 60 in the primary circuit of a transformer 61 which supplies through the rectifying devices 62 a grid potential to the grids of the control tubes 35. The variable resistance 60 may be controlled in response to any desired operating condition and is herein shown as being controlled in response to the terminal voltage of the direct-current circuit 11.

To further increase the utility of the control system, it is frequently desirable to have a completely self-contained automatic control of the valves 35 responsive to the state of the charge on the capacitor 22 and to control the phase relation of the charging potential applied to the capacitors 22 to regulate some characteristic of the converter. I have found that instead of utilizing a phase shifting device 20 and an impedance 23, space and weight may be saved by utilizing phase shifting reactors 65 which satisfactorily perform both the phase shifting and current control functions for a reasonably wide range of control. The phase controlling reactors 65 comprise a three-legged reactor core 66, on the outer legs of which are the windings 67, and on the middle leg a winding 68 supplied with direct current from some suitable source such as the full-wave rectifier 69, the direct-current output of the rectifier 69 being varied in proportion to some value of the load which it is desired to regulate by some responsive device such as the silverstat 60 responsive to some control characteristic such as the output voltage of the converter. The phase control of the charging potential is obtained by varying the amount of current flowing in the windings 68 and so varying the reactance of the reactors 65.

Automatic control of the firing time of the valves 35 is obtained by means of a negative bias obtained from a full-wave rectifier 75 supplied from a voltage divider 76 connected across the capacitor 22. While several types of voltage dividers 76 may be used, I prefer to use a simple wound resistor as they are standard articles of manufacture and occupy a minimum of space.

The output of the rectifier 75 is stabilized by a capacitor 77 and a voltage 136 (see Fig. 9) is taken from a portion of a resistor 78 connected

across the output of the rectifier 75 and applied between grid 36 of tube 35 and the positive terminal 79 of rectifier 75.

A variable positive impulse is supplied to grid 36 by means of a voltage divider connected across the capacitor 22 and an impedance 80 connected between the voltage divider and the junction 33 between rectifiers 29 and 30. Preferably, the voltage divider connected across the capacitor 22 comprises a resistor divided into two parts 81 and 82 with a mid-tap 83. Likewise, the impedance 80 may be a simple commercial resistor.

The operation of the system is as follows: assuming potential applied to the excitation system so that positive potential flows through resistor section 81, impedance 80 and rectifier 30 to the capacitor 22, the potential between points 79 and 33 will be proportional to the potential of capacitor 22. The portion of impedance 80 included between 79 and 33 is so selected that the voltage 180 rises to a value sufficient to trip the grid 36 at or near the maximum charge on the capacitor 22. The discharge of capacitor 22 reduces the voltage 180 to a value where potential 136 again makes grid 36 negative and care must be taken that any follow charge on the capacitor 22 does not increase 180 to a value which might produce false operation of valve 35. On the alternate half-cycle, the positive potential flows through 82—33—29 and since the current in impedance 80 is unidirectional, the second peak is also positive and trips the grid to fire the alternate igniter.

An impedance 85 is usually inserted in series with valve 35 in order to control the discharge impulses of the capacitor 22, and a capacitor 86 is shunted between the grid 36 and the cathode of valve 35 to prevent false operation by any stray or transient impulses.

In a practical embodiment of the control system of Fig. 8 with capacitors 22 of 8 to 16 microfarads, the phase voltage of transformer 21' was of the order of 300 to 500 volts, the impedances 81 and 82 were commercial wound resistors of 10,000 ohms each, while impedance 80 was a similar resistor of 3000 ohms with a sliding contact and impedance 85 was of 5 ohms. It is apparent that these valves are dependent on the characteristic of valve 35 and the electrodes 17.

While for purposes of illustration, I have shown and described several specific embodiments of my invention, it will be apparent that changes and modifications can be made therein without departing from the true spirit of my invention or the scope of the appended claims.

I claim as my invention:

1. In an electric current translating system, for transferring electric energy between two dissimilar electric circuits, having at least a pair of alternately conducting electric valves, a control system comprising a capacitor, circuits for charging said capacitor alternately in opposite polarity, an exciting electrode in each of said valves, a discharge circuit connecting said exciting electrodes to opposite terminals of said capacitor, a common connection between said exciting electrodes, polarity responsive circuit means connected to both terminals of said capacitor, a return circuit from said common connection to an intermediate point of said polarity responsive circuit means, a controlled electric valve in said return circuit and a polarity selective device connected in series circuit relation between each of said exciting electrodes and said capacitor.

2. An electric current translating system for

transferring electric energy between two dissimilar electric circuits comprising at least a pair of alternately conducting valves, a capacitor, means for charging said capacitor in alternate polarity, an exciting electrode in each of said valves, a discharge circuit for connecting one of said exciting electrodes to one terminal of said capacitor and the other exciting electrode to the opposite terminal of said capacitor, polarity responsive circuit means connected to both terminals of said capacitor, an intermediate connection in said circuit means, said circuit means being alternately conductive from said intermediate connection to the alternate terminals of said capacitor, a return circuit from a point intermediate said exciting electrodes to said intermediate connection of the circuit means, a grid controlled mercury cathode electric valve in said return circuit and polarity responsive means connected in series circuit relation to each of said exciting electrodes.

3. An electric current conversion system comprising at least a pair of alternately conducting valves each of said valves including a main anode, a vaporizable cathode and a make-alive electrode, a source of alternating control potential, a capacitor connected to be charged from said source, connections from the opposite sides of the capacitor to the respective make-alive electrodes, unidirectional conductors in each of said connections, a pair of oppositely disposed unidirectional conductors connected across said capacitor, a unidirectional return circuit from the cathodes of said valves to a point intermediate said oppositely disposed unidirectional conductors and a controlled electric valve in said return circuit.

4. An electric current conversion system comprising at least a pair of alternately conducting valves each of said valves including a main anode, a vaporizable cathode and a make-alive electrode, a source of alternating control potential, a capacitor connected to be charged from said source, connections from the opposite sides of the capacitor to the respective make-alive electrodes, polarity responsive means for controlling current flow in said connections, oppositely disposed unidirectional conducting devices connected across said capacitor, a connection from the cathodes of said valves to a point intermediate said unidirectional conductors and a controlled electric valve in said connection.

5. An electric current conversion system comprising a pair of alternately conducting electric valves, means for impressing potential across said valves, an exciting electrode in each of said valves, a source of alternating control potential, capacitor means connected to be charged from said source of control potential, a discharge circuit for said capacitor means, including circuit means for connecting said exciting electrodes to opposite terminals of said capacitor means, a unidirectional conductor in series circuit relation with each of said exciting electrodes, a common turn connection from said exciting electrodes, oppositely disposed polarity responsive circuit means connected between the return circuit and the opposed terminals of said capacitor means, a grid controlled discharge device in said common return connection.

6. An electric current conversion system comprising a pair of alternately conducting electric valves, means for impressing potential across said valves, an exciting electrode in each of said valves, a source of alternating control potential, capacitor means connected to be charged from said source of control potential, a discharge circuit for

said capacitor means including circuit means for connecting said exciting electrodes to opposite terminals of said capacitor means, a unidirectional conductor in series circuit relation with each of said exciting electrodes, a common return connection from said exciting electrodes, opposed unidirectional conductors selectively connecting the return circuit in conductive relation to the opposed terminals of said capacitor means, a grid controlled discharge device in said common return connection, and means responsive to the potential of said capacitor for supplying control potential to the grid of said grid controlled valve.

7. An electric conversion system comprising at least a pair of alternately conducting vapor electric valves, each of said valves including a main anode, a vaporizable reconstructing cathode, and a make-alive electrode in contact with said cathode, a capacitor, means for cyclically charging

20 said capacitor in opposite polarity, circuit means including a common cathode connection for connecting said make-alive electrodes across said capacitor, a unidirectional conductor in series with each of said make-alive electrodes, oppositely disposed unidirectional conductors connected across said capacitor, a return circuit from said common cathode connection to a point intermediate said oppositely disposed unidirectional conductors and a controlled electric valve in said return circuit.

8. An electric conversion system comprising at least a pair of alternately conducting vapor electric valves, each of said valves including a main anode, a vaporizable reconstructing cathode, and a make-alive electrode in contact with said cathode, a capacitor, means for cyclically charging

35 said capacitor in opposite polarity, circuit means including a common cathode connection for connecting said make-alive electrodes across said capacitor, a unidirectional conductor in series with each of said make-alive electrodes, oppositely disposed unidirectional conductors connected across said capacitor, a return circuit from said common cathode connection to a point intermediate said oppositely disposed unidirectional conductors and a controlled electric valve in said return circuit, and means to control said controlled electric valve to periodically establish a cathode spot in alternate ones of said valves.

9. In an electric conversion system having a pair of alternately conducting electric valves, a control system comprising an exciting electrode for each of said valves, a source of alternating control potential, a capacitor connected to a said source to be charged therefrom during each half-cycle of the source potential, a bridge-type rectifier connected across the terminals of the capacitor with the exciting electrodes connected in series circuit relation in alternately conducting arms of the bridge connected rectifier and a grid controlled discharge device connected across the unidirectional terminals of said bridge-type rectifier.

10. In an electric conversion system having a pair of alternately conducting electric valves, a control system comprising an exciting electrode for each of said valves, a source of alternating control potential, a capacitor connected to said source to be charged therefrom during each half-cycle of the source potential, connections from the opposite sides of said capacitor to the respective excitation electrodes, unidirectional conductors in each of said connections, a return circuit from said excitation electrodes, impedance means connecting said return circuit to both

sides of said capacitor and a grid controlled electric valve in said return connection.

11. An electric current conversion system for interconnecting an alternating-current circuit and a direct-current circuit comprising a pair of alternately conducting valves, each of said valves including a main anode, a mercury cathode and an exciting electrode associated with said cathode, a capacitor, means for charging said capacitor in opposite polarity for succeeding half-cycles of the potential applied to said valves, a winding connected across said capacitor, connections including a common cathode connection for said valves connecting said exciting electrodes to opposite terminals of said winding, polarity responsive means in series with each of said exciting electrodes, a return connection from said common cathode connection to an intermediate tap in said winding and a controlled electric valve in said return connection.

12. An electric current conversion system for interconnecting an alternating-current circuit and a direct-current circuit comprising a pair of alternately conducting valves, each of said valves including a main anode, a mercury cathode and an exciting electrode associated with said cathode, a capacitor, means for charging said capacitor in opposite polarity for succeeding half-cycles of the potential applied to said valves, a winding connected across said capacitor, connections including a common cathode connection for said valves connecting said exciting electrodes to opposite ends of said winding, a return connection from said common cathode connection to an intermediate tap in said winding, a controlled electric valve in said return connection, and a unidirectional conductor in series with each of said exciting electrodes.

13. In an electric conversion system having at least a pair of alternately conducting electric valves, a control system for said valves comprising an exciting electrode in each of said valves, a source of alternating control potential, a capacitor connected to said source to be charged to alternate polarity during successive half-cycles of said source, connections from the opposite sides of said capacitor to the respective exciting electrodes, each of said connections including a unidirectional conductor, a return circuit from said exciting electrodes, impedance means connecting said return circuit to both sides of said capacitor and an electric valve in said return circuit for controlling the application of exciting impulses to said exciting electrodes.

14. An electric current translating system comprising at least a pair of alternately conducting vapor electric valves, a make-alive type exciting electrode in each of said valves, a capacitor, means for charging said capacitor in alternate polarity, an intermediate terminal between said make-alive electrodes, a connection from one side of said capacitor to one of said make-alive electrodes, a connection from the opposite terminal of the capacitor to the other make-alive electrode, a return connection from the intermediate terminal, circuit means including a pair of oppositely disposed unidirectional conductors connecting said return circuit to both sides of said capacitor, a controlled electric valve in said return connection for controlling flow of current from said capacitor to said make-alive electrodes and polarity responsive means for determining which of said make-alive electrodes is energized by said current flow.

15. A control system for a pair of alternately

conducting vapor electric valves comprising a make-alive electrode in each of said valves, a source of alternating control potential, capacitor means, connections for cyclically charging said capacitor means in alternate polarity, circuit means for supplying energy from said capacitor to each of said make-alive electrodes, said circuit means including polarity responsive means in series with each of said make-alive electrodes, a winding connected across said capacitor means, an intermediate connection in said winding, a common return circuit from said make-alive electrodes to said intermediate connection and a single controlled discharge device in said common return circuit for controlling current flow to each of said make-alive electrodes.

16. A control system for a pair of alternately conducting vapor electric valves each of which includes at least a vaporizable cathode, an anode and a make-alive electrode, comprising capacitor means, means for alternately charging said capacitor means in opposite polarity, winding means connected to opposite sides of said capacitor means, an intermediate connection in said winding means, a single controlled unidirectional discharge device for controlling current flow through said winding means and polarity responsive circuit means for impressing the potential of said winding means on said make-alive electrodes.

17. In an electric conversion system having at least a pair of alternately conducting electric valves of the make-alive type, a control system comprising a make-alive electrode in each of said valves, a source of alternating control potential, a capacitor connected to be charged from said source in alternate polarity by alternate half-cycles of said source, a bridge-type rectifier connected across the terminals of said capacitor, the respective make-alive electrodes of said alternately conducting valves connected in series circuit relation in alternately conducting arms of said bridge-type rectifier, a grid-controlled electric valve connected across the direct-current terminals of said bridge-type rectifier, and a resistance network energized by the potentials across the capacitor impressing control potential on the grid of said grid-controlled electric valve.

18. In an electric conversion system having at least a pair of alternately conducting electric valves of the make-alive type, a control system comprising a make-alive electrode in each of said valves, a source of alternating control potential, a capacitor connected to be charged from said source in alternate polarity by alternate half-cycles of said source, a bridge-type rectifier connected across the terminals of said capacitor, the respective make-alive electrodes of said alternately conducting valves connected in series circuit relation in alternately conducting arms of said bridge-type rectifier, a grid-controlled electric valve connected across the direct-current terminals of said bridge-type rectifier, a voltage divider connected across the capacitor, a full-wave rectifier fed from said voltage divider, connections impressing the output potential of said full-wave rectifier on the grid of said grid-controlled electric valve, a second voltage divider connected across the capacitor, an intermediate connection in said voltage divider, an impedance connected between the negative terminal of the bridge-connected rectifier and the intermediate connection of said voltage divider and connections for impressing a voltage across a portion of said impedance on the grid of said grid-controlled valve.

19. An electric current conversion system comprising at least a pair of alternately conducting valves each of said valves including a main anode, a vaporizable cathode and a make-alive electrode, a source of alternating control potential, a capacitor connected to be charged from said source, connections from the opposite sides of the capacitor to the respective make-alive electrodes, polarity responsive means for controlling current flow in said connections, oppositely disposed unidirectional conducting devices connected

16

across said capacitor, a connection from the cathodes of said valves to a point intermediate said unidirectional conductors and a controlled electric valve in said connection, a resistance network connected across said capacitor, a portion of said network being in shunt with said oppositely disposed unidirectional conductors and a connection from said network to the grid of said grid-controlled valve.
